UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIE-BLOCK.

1,108,958.

Specification of Letters Patent.

Patented Sept. 1, 1914.

Application filed November 29, 1913. Serial No. 803,671.

To all whom it may concern:

Be it known that I, RICHARD LESTER WILCOX, a citizen of the United States, residing at Waterbury, in the county of New Haven and State of Connecticut, have invented certain new and useful Improvements in Die-Blocks, of which the following is a specification, reference being had therein to the accompanying drawings.

10 The invention herein shown and described relates to a die block of the type used in a heading machine for holding the dies, and has for its object, among other things, to so design and construct the several parts of 15 the block that the body member thereof may be attached to the header and not require removal therefrom to adjust the dies, or for any similar reason, and to connect there-with a cap or cover that may be readily 20 moved into and out of its closed position without separation from the body member and with the minimum labor and incon-venience.

With these objects in view, my invention 25 consists in the die block, having certain details of construction and combinations of parts, as will be hereinafter described and more particularly pointed out in the claims.

Referring to the drawings, in which like 30 numerals of reference designate like parts in the several figures; Figure 1 is a side view of my improved die block; Fig. 2 is a front view; Fig. 3 is a plan view; and Fig. 4 is a sectional view of the cap or cover, 35 taken upon line A—B of Fig. 2.

The prior art discloses generally two types of header die blocks, one type requiring removal of the block with its connecting parts, as a unit, from the header to have access to 40 the dies, an operation requiring much labor and strength, and involving serious difficulties in the fine relative adjustment of the several parts; another type, differing only in that the body of the die block is held 45 within the header while the cover or cap is removed therefrom.

In the type of die block herein shown and described the body member thereof is permanently and adjustably secured within the 50 body of the header and the cap or cover hinged thereto, which enables me to obtain all of the advantages of the latter, of the above described types of die blocks and the added advantage of a movable cap or cover

that can be moved into and out of its closed 55 position without removal from the machine, with the minimum inconvenience and without the aid of special apparatus or an unusual amount of labor.

In the embodiment of my invention there 60 are two principal elements, the first being the body member 1 that is secured within the header by any convenient means common in the art, and substantially L shape in side elevation, as shown in Fig. 1, carrying an 65 adjusting screw 2, common to all types of die blocks, whereby the body member may be adjusted within the header. The other principal element is the cap or cover 3 that is pivotally secured to the body member 1 70 by the pin 4 that passes through the lugs 5 integral with the cap. This cap is secured to the body member 1 in its closed position by the bolts 7 that pass through one wall of the body member and slotted openings 75 8 in the cap, with nuts 9 threaded thereon. The slotted openings 8 are of such size and shape as to permit the cap to pass over the bolts when the nuts 9 are removed and while being moved upon its pivot mounting. 80 When the cap is in its closed position there is an open space 10 between the underside thereof and the horizontal portion of the body member, in which the dies (not shown) are movably mounted upon the hardened 85 plate 13, being held against endwise movement by the plate 11 that is secured by screws 12. The wire being fed to the dies passes through the hardened bushing 14 fixed within the vertical portion of the body 90 member. A plurality of die separators 15, of the usual type, are slidably mounted within the cap 3, and are pressed downwardly by spring fingers connected with a fixed part and not herein shown. In the 95 front face of the cap 3 is a lifter opening 16 of substantially the same diameter as that of the separators 15, and designed to receive one of the separators, as shown by broken lines in Fig. 1, whereby convenient means 100 is provided for manipulating the cap or cover when it is desired to swing the same upon its pivot mounting.

In the drawings the several parts are shown in the relative positions occupied by them when the dies are mounted on the body member and held against upward movement by the cap or cover. When it is

desired to gain access to the dies, the nuts 9 are removed from the bolts 7, one of the separator pins 15 is placed in the lifter opening 6, and the operator grasps the projecting end thereof and swings the cap upwardly to its open position, shown by broken lines in Fig. 1, the slots 8 permitting the cap 3 to pass over the end of the bolts 7. To return the cap or cover to its closed position, the operations are reversed and the nuts 9 are threaded upon the bolts 7.

With this improved die-block, the minimum amount of labor is involved in obtaining access to the dies, and at no time is the cap or cover removed from the machine.

The details of my invention may be varied, and I desire therefore to have it understood that I do not limit myself to the exact construction herein shown and described, but claim all that falls fairly within the spirit and scope of my invention as defined by the claims herein.

Having described my invention, what I claim as new and desire to secure by Letters Patent, is:—

1. In a die block, the combination with a body member; of a cap pivotally connected therewith; and means for securing said cap to said body member in its closed position.
2. In a die block, the combination with a body member; of a cap or cover; means for pivotally securing the same to said body member; means for securing said cap to said body member against movement when in its closed position, said means permitting the movement of the cap from its open to its closed position without affecting the relative position of such means in said body member.
3. In a die block, the combination with a body member, having two walls at an angular relation to each other; of a cap; means for pivotally securing said cap to said body member; and threaded means for securing said cap to said body member when in its closed position.

4. In a die block, the combination with a body member; of a cap; means for inseparably and movably securing said cap to said body member, whereby it may occupy at different points of its movement a closed or an open position in relation to said body member; and means for securing said cap to said body member when in its closed position.

5. In a die block, the combination with a body member, having two walls at an angular relation to each other; of a retaining bolt fixed therein, the end thereof projecting through one wall thereof and over the other wall; a cap; and means for pivotally securing said cap to said body member, said cap passing over the projecting end of said bolt while being moved from its closed to its open position, and vice versa.

6. In a die block, the combination with a body member, having two walls at an angular relation to each other; of one or more bolts fixed therein with a portion thereof projecting through one wall thereof and over the other wall; a cap, having a lifter opening in one face thereof and slotted openings therethrough in such relative position with said bolts as to permit the same to pass therethrough; and means for pivotally securing said cap to said body member.

In testimony whereof I affix my signature in presence of two witnesses.

RICHARD LESTER WILCOX.
